UNITED STATES PATENT OFFICE.

LAWRENCE J. KLEMM, OF ALLEGHENY, PENNSYLVANIA.

APPARATUS FOR RINGING GONGS.

SPECIFICATION forming part of Letters Patent No. 634,005, dated October 3, 1899.

Application filed April 17, 1899; Serial No. 713,299. (No model.)

To all whom it may concern:

Be it known that I, LAWRENCE J. KLEMM, a citizen of the United States of America, residing at Allegheny, in the county of Allegheny and State of Pennsylvania, have invented certain new and useful Improvements in Apparatus for Ringing Gongs; and I do hereby declare the following to be a full, clear, and exact description thereof, reference being had to the accompanying drawings, which form a part of this specification.

My invention relates to an improved apparatus for ringing gongs upon street-railway and other cars; and it consists in the certain details of construction and combination of parts as will be fully described hereinafter.

In the accompanying drawings, Figure 1 is a side elevation of a portion of the front of a street-railway car, showing my improved apparatus arranged in connection with the brake-lever. Fig. 2 is a plan view of the same. Fig. 3 is an enlarged detail plan view of the apparatus having the gong removed therefrom the better to show the concealed parts. Fig. 4 is a front elevation of the same, showing the gong in position. Fig. 5 is a sectional detailed view of one of the spring-arms, showing the flexible spring-hinges against which the operating-bar engages, said section on line X X. Fig. 6 is a perspective view of the operating-bar, showing the projections for engagement with flexible or spring clips.

To construct a bell-ringing apparatus in accordance with my invention, I attach to the handle 3 of the brake-operating lever a sprocket-wheel 4 and connect the same by a suitable chain to a smaller similar wheel 5, mounted upon the lower end of a vertical rod 6, mounted in proper bearing and having at its upper extremity a short crank 7. This crank 7 is connected by a short link 8 to a bar 9, arranged in a horizontal position beneath the bell or gong 10 it is desired to operate, and the said rod held and permitted to slide in bearing. Formed upon the outer end of this rod 9 is a projection 21, and at a suitable point some distance away another projection 20, which serves as a means of engagement with spring-hinged parts 18, attached to the spring tapper-arms 14. These arms are pivoted to bolts 15, held in brackets 12, rigidly

attached by bolts to the top of the car 1. Connecting these two spring tapper-arms 14 is a spring 17, and the said arms limited in this inward movement by stops 16.

55

The spring parts above mentioned consist of a downwardly-projecting hinged piece 18, attached to each tapper-arm 14 and limited in its rotatable movement when drawn in one direction to resist the pressure of the projections 20 and 21 while the tappers are drawn away from the gong and to permit the said projections to pass freely beneath upon the return movement of the bar 9. These hinge-pieces 18 are each provided with a spring to hold the said pieces when at rest in the position shown at Fig. 5 on the drawings.

In operation at each slight movement of the brake-lever 3 the motion is transmitted through the sprockets 4 and 5 to give a rotary motion to the small crank 7. This crank motion reciprocates the rod 9, and the projections 20 and 21 alternately being brought in contact with the flexible hinges 18 will draw the tappers back until released by the said projections passing to one side of the hinged pieces while the same are traveling in the arc of a circle, thereby vibrating the tapper-arms 14, and as the said arms have sufficient spring or flexibility will strike the gong repeatedly and at each back-and-forward movement of the operating-bar.

It is obvious that various slight modifications may be made in the mechanical details of my apparatus without departing from the spirit of the invention.

Having thus described my invention, I claim—

1. In combination with a rotatable brake-lever of a railway-vehicle, a sprocket connected therewith for transmitting a reciprocating movement to a bar arranged to operate the tappers of a gong, the said bar being mounted in suitable slides and provided with projecting portions to engage with flexible attachments secured to the pivoted tapper-arms, whereby each back-and-forward movement of the said bar will vibrate the tappers and strike the gong or bell, as described.

90

100
2. An apparatus for ringing gongs, consisting of the sprocket connections 4 and 5, the vertical crank-bar 6, the operating-bar 9, con-

ected thereto, the projections 20, 21, formed upon the said bar, the pivoted tappers 14, the spring 17, and stops 16, and the flexible hinged parts 18, pivoted with spring 19, all arranged and combined for service, substantially as and for the purpose described.

In testimony whereof I have hereunto af-

fixed my signature in the presence of two subscribing witnesses.

LAWRENCE J. KLEMM.
